No. 3492

3 of 3

United States Patent Office.

HENRY JOHNSON, OF WAUREGAN, CONNECTICUT.

Design No. 3,492, dated May 11, 1869.

DESIGN FOR A SET OF BLOCKS FOR AN ALPHABET-PUZZLE.

The Schedule referred to in these Letters Patent and making part of the same.

To all whom it may concern:

Be it known that I, HENRY JOHNSON, of Wauregan, in the county of Windham, and State of Connecticut, have originated and designed a new Form of Alphabet-Block Puzzle; and I do hereby declare that the following is a full, clear, and exact description of the same, reference being had to the annexed drawings, making a part of this specification.

The sheets of the drawings marked 1 and 2 represent the various blocks of my design, formed into letters, and sheet marked No. 3, shows the form of all the blocks used in forming the letters.

My blocks are forty-eight in number, and they all appear in each of the letters, except in the letters A, M, V, and W. In these letters one block is omitted.

The sheet of drawings marked No. 3, constitutes

the basis of this application for a design patent, the other sheets being filed as collateral papers.

The form of my blocks respectively is represented on said sheet 3, and it is for such form only that this application is made.

What I claim as my invention, and desire to secure by Letters Patent, is—

The alphabet-puzzle blocks, herein set forth and shown.

In testimony that I claim the above, I have hereunto subscribed my name, in the presence of two witnesses.

HENRY JOHNSON.

Witnesses:

NELSON P. ALDRICH,
CALEB P. WILSON.
